2 SHEETS—SHEET 2.

UNITED STATES PATENT OFFICE.

ALBERT H. BUCKELEW, OF NEWARK, NEW JERSEY

INDICATOR FOR AUTOMATIC ELEVATOR SYSTEMS.

No. 922,849.

Specification of Letters Patent.

Patented May 25, 1909.

Application filed March 29, 1907. Serial No. 365,322.

To all whom it may concern:

Be it known that I, ALBERT H. BUCKELEW, a citizen of the United States, residing at Newark, in the county of Essex and State 5 of New Jersey, have invented certain new and useful Improvements in Indicators for Automatic Elevator Systems, of which the following is a full, clear, and exact specification.

10 This invention relates to indicators for automatic elevator systems, and has particular reference to mechanism to be used in connection with a push button controlled elevator to indicate on the various floors, the 15 condition of the car itself and also that of the various circuits.

In push button controlled elevator systems, it is frequently impossible for an intending passenger to determine the condition 20 of the system, as whether the car is in use, or in case of no response to a signal, whether a door has been left open, or to know if the car is coming in response to the signal.

The present invention has for its object to 25 provide an indicating system in combination with non-interfering mechanism, whereby an intending passenger, upon operating a starting or signaling button at any floor, will be apprised by automatically responsive devices 30 as to the condition of the elevator system. That is to say, a signal will indicate whether the car is ready for use, or busy, whether it is coming to the floor in response to a call, or whether it is not responding to 35 the call, as by reason of a door having been left open, or some other disarrangement of the system present, preventing operation of the car by the controlling push button.

In carrying out the invention, a plurality 40 of signals are provided to indicate various conditions, and one or another of these signals will be automatically operated to indicate to the intending passenger just what the condition of the elevator system is, and 45 thereby prevent useless waiting for the car in case some condition, not necessarily manifest, prevents its operation. In connection with such mechanism, means is provided for automatically throwing out of operation the 50 other signals until a change of condition occurs such as to restore the signal first made, and makes suitable changes at other floors to correctly indicate the condition of the system with respect thereto.

The invention is shown diagrammatically 55 in the accompanying drawings, wherein—

Figure 1 is a sectional view of a signal box at a floor; Fig. 2 is a front view; Fig. 3 is a rear view; Fig. 4 a detail plan view showing the shutter arrangement; Fig. 5 a plan view 60 of the actuating switch, and Fig. 6 a diagram of the circuits for two floors.

In carrying out the invention a signal, as a lamp 1, is illuminated through a dial 2 whenever the controlling push button 3 is 65 operated. Under normal conditions of rest, when the car is ready to start, no indication will be made, but as soon as the push button 3 is operated, switch 26 is closed at that floor, thus completing the circuit from 70 wire M through wire J to wire L, Fig. 6, and lighting the lamp 1. At this point, several conditions may be present, which it is desirable to indicate to the person operating the button 3. The car may be busy, which 75 should be made known or it may be coming to the floor, or a well door or car gate may be open, in which latter case the car cannot be operated until the door and gate are shut, or no indication may be showing, as 80 when the car is ready for use. By the mechanism to be described, either of these conditions will be automatically indicated to the intending passenger, and suitable indications made at the other floors. 85

Whenever the car is in operation, it is desirable to indicate this fact at each floor, and this is accomplished by means of magnets 9 at each floor, in series, and connected with a supply wire H. From the last 90 magnet 9 a wire G leads to a switch 32, normally open, and thence to return wire L. A "busy" magnet 40, which is always energized when the car is in operation, controls switch 32. Whenever switch 32 is closed, 95 the magnets 9 on all the floors will be energized and actuate a signal, to be hereinafter described indicating this fact, and also by suitable locking out mechanism, preventing interference while the car is in 100 operation, since switch 32 opens whenever magnet 40 is deenergized. 30, 31, are direction switches, one for each floor and connected with the car in a well known manner as to throw over successively as the 105 car passes from floor to floor, but only one of the direction floor switches will have current at a time, and the car will stop

when this switch opens and deenergizes the one or the other of direction magnets 45, 46, which was energized when the switch 27 was closed by button 3. Upon closing starting switch 27, say at floor 1, the circuit, starting from wire $-$, Fig. 6, will be through "busy" magnet 40, wire P, magnet 41 on the right, wire D, switch 27 at floor 1, magnet 7, wire B, floor switch 31, corresponding to floor 1, wire Y, magnet 46, wire 61 to wire $+$. The magnet 46 will attract armature 63, which will operate a main motor switch, not shown, or other power controller, such as a valve for a hydraulic motor in a well known manner, and start the car. When the car opens switch 31, as it will be predetermined to do at floor 1, it will be stopped by the deenergization of magnet 46. Magnet 45 is similarly controlled to start the car in the other direction. The magnets 41 are relay magnets controlling switches 42, so that the holding current, while the car is running, passes through switches 42 and the floor switches open the circuit and deenergize the magnets 41.

The opening of the circuit likewise deenergizes the magnets 9 and opens the switches 26 and 27, restoring the signals actuated by magnets 9 and also putting out the lights when switches 26 open. It will also be seen that if the car cannot respond to a signal from the push button, no indication will be made by magnet 7, to show that the car is coming, since the switch 27 will be locked out and cannot be closed. The switch 26 closes in advance of the switch 27 and can always be closed to light the lamp and illuminate whichever of the drops controlled by magnets 7, 8, 9, that happens to be energized. In daylight, the drops will be visible without the lamp, but it is desirable to have the lamp and to only light it when the car is to be used.

To indicate when a door is open, door switches 37, 38, etc., at each floor are provided, these switches being in series on wires S, S', and are closed when the doors are all closed. In shunt across wires S, S', is a magnet 47, and resistance R² which is shunted out of action when the door switches are all closed. When any door is opened, magnet 47 attracts its armature and closes switches 33, thereby sending current through wire K F to the magnets 8 at each floor and energizing them, thereby making an indication at each floor. In cases where the car is provided with a gate, a similar arrangement controlled by a magnet 48 in a shunt across a door switch on the car is used, and also magnet strength controlling resistance R-1, as before described. The magnet 48 actuates a switch 34 which controls the circuit of magnet 8 similarly to switch 33. When the door or gate is again closed the indication 65 will be removed.

Figs. 1, 2, 3, 4 and 5, show the specific indicators and the locking out mechanism. Each of the magnets 7, 8 and 9, has a pivoted armature 12, 16, 18, respectively, which when the magnet is energized, moves downward. Each of these armatures is connected to a frame 5 by wires, as 17. The frames 5, are counterweighted and pivoted on a common axis 6, and also carry the shutters 15, 14, 20, indicating respectively open door, car coming and car busy conditions. The armature 12 is connected to actuate shutter 14 through arm 11, the armature 16 similarly actuates shutter 15 by arm 13, and armature 18 similarly actuates shutter 20 by arm 19, it being observed in Fig. 1 that the shutters nest one within another. The push button 3 mechanically actuates a pivoted double switch blade 23 to close by contacts 24, 25, the switches 26, 27, Figs. 1 and 5. The switch 23 is rigidly attached to armature 12 of magnet 7 and the latter also moves down and raises the shutter 14, but if the car is not coming, the magnet 7 will not be energized and weight 25 on frame 20 will throw out the switch. If however, either of magnets 8 or 9 receives current its armature will be drawn down, and the frame 23 having been thrown up by the weight, will be locked out. This is by reason of lugs 22 on frame 23 being unable to pass lugs 21 on the armature 16 or 18 which was pulled down by its magnet 8 or 9. It will thus be seen that if switch 27 is locked out by reason of energization of either of magnets 8 or 9, the "coming" magnet 7 cannot be energized, since the switch 27 is closed by button 3 unless locked out by the energization of one of the magnets. It will thus appear, that while a door is open or the car is busy, the "coming" magnet 7 cannot be energized, since the push button 3 and switch 27 are electrically locked out in such contingencies. This forms a non-interference arrangement for all floors preventing closing of any other starting switch 27, until the one closed is thrown out, or the locking out lugs withdrawn. A passenger can ascertain by operating button 3, if the car is in condition for use. If the signal "coming" shows, whether the lamp be lighted by switch 2d or not the car will start, or if there is no indication at dial 2, he will know that the car can be operated by switch 27, whereupon the signal "coming" will show as long as the starting circuit of switch 27 is held closed, which will be as long as any one of magnets 7, 8 or 9 holds the switches 27 and 26 closed, these switches preferably being connected to work simultaneously, though this is not essential.

It will be obvious that the usual car controlling devices, as stop buttons, car starting switches on the car, etc., will be used where desired, but these are not essential to a full understanding of the invention. Also, the

invention with respect to certain features thereof is not to be restricted to use in connection with automatic elevators, as it is equally valuable with elevators in which the

5 shafts are closed and it is not possible to see the car and ascertain whether any response has been made by the operator to a call.

The invention may be changed and modified in various ways without departing from 10 the scope thereof, and I do not restrict myself to the precise construction herein shown.

Having thus described my invention, I declare that what I claim as new and desire to secure by Letters Patent, is,—

15 1. The combination with an automatically controlled elevator system, of a signal for automatically indicating at a floor when a well door is open, and a light controlled by the starting switch for illuminating said signal, substantially as described.

20 2. The combination with an automatically controlled elevator system, of means for automatically indicating at a floor, when a well door is open, and means controlled by said indicator preventing interference with the car, substantially as described.

25 3. The combination with an automatically controlled elevator system, of means for automatically indicating certain varying conditions of the system, and a single switch for controlling certain other indications and the starting of the car, substantially as described.

30 4. The combination with an elevator system and controlling means therefor, of a plurality of signaling devices at a floor, one being responsive to a starting signal corresponding to that floor, and the other automatically indicating that the car is in use, substantially as described.

35 5. The combination with an elevator system, and means for calling the car to a certain floor from any other floor, and door switches controlling the operation of the car, of means for automatically indicating at said floor whether the door circuit is in condition to permit starting of the car in response to the signal, said automatic indicator in one position preventing signaling the car, substantially as described.

40 6. The combination with an elevator system and means for calling the car to a certain floor from any other floor, of means automatically indicating that the car is in use and automatically preventing signaling of the car when in indicating position, substantially as described.

45 7. The combination with a plurality of electro-responsive indicators and an elevator controlling switch, of means whereby one indicator when in operation locks out the others, substantially as described.

50 8. The combination with a plurality of indicators automatically indicating varying conditions of an elevator system, and a con-

trolling switch, of means whereby one indicator automatically locks out the other and the starting switch, substantially as described.

55 9. The combination with a plurality of indicators automatically indicating varying conditions of an elevator system, and a controlling switch, of means whereby one indicator automatically locks out the other, and means automatically restoring the indicator when the car stops, substantially as described.

60 10. The combination with an electrically controlled elevator, of an indicator for automatically indicating a condition of the system, controlling switches for the elevator, and means whereby said indicator automatically prevents control of the car by said controlling switches, substantially as described.

65 11. The combination with an elevator system and controlling means therefor, of a plurality of signaling devices at a floor, one being responsive to a starting signal corresponding to that floor and the other automatically indicating that the car is in use, and means preventing actuation of the starting signal for that floor when the automatic signal is in use, substantially as described.

70 12. The combination with an elevator system and means at a floor for bringing the car to that floor from any other, of a plurality of separately controlled signals at that floor for indicating the condition of the system with respect to that floor, certain of said signals being automatically responsive to signals from other floors, and one signal being responsive to said starting means at that floor and means whereby actuation of any signal automatically prevents actuation of the others, substantially as described.

75 13. The combination with an elevator system and means for calling the car to a certain floor from any other floor, of means for indicating whether or not the car can respond to the signal, automatically controlled indicators and starting means at the other floors, said indicators being responsive to the starting of the car and automatically preventing actuation of the starting means, substantially as described.

80 14. The combination with an electrically controlled elevator system, of means whereby upon opening the circuit the car is stopped, starting means for the car at the various floors, automatic indicators for the various floors controlled by the car controlling circuit and preventing actuation of the starting means when, in operation, and means for releasing the indicators when the car controlling circuit is opened, substantially as described.

85 15. The combination with a starting switch at each of a plurality of floors, of a magnet at each floor controlled by any one of said switches, a signal actuated by the

magnet at the floor from which the signal was sent to indicate that the car is responding to said signal, and different signals at the other floors actuated by the magnets at said floors to indicate that the car is responding to a signal from some other floor.

16. In an automatic elevator system, the combination with a starting switch, of a plurality of independent locking devices for preventing actuation of said switch, one of said locking devices being controlled by a door circuit, and the other by the starting switch of another floor.

17. In an automatic elevator system, the combination with a starting switch, of a plurality of independent locking devices for preventing actuation of said switch, one of said locking devices being controlled by a door circuit, and the other by the starting switch of another floor, and indicators respectively indicating which of said locking devices is effective.

18. The combination with an automatic elevator and a starting switch, of a plurality

of indicators for indicating the condition of the car system, means controlled by either of said indicators for preventing closure of said switch to start the car, a lamp for illuminating said indicators and a controlling switch for said lamp circuit capable of being closed at any time by said starting switch.

19. The combination in an automatic elevator system of a single circuit containing a plurality of door switches in series, a magnet circuit in shunt across said circuit, a switch controlled by said magnet and normally open when the door switch circuit is closed, and an indicator circuit containing said switch and a plurality of indicators at the floors and controlled by said switch whereby to indicate at the floors when a door is open.

In testimony whereof I affix my signature, in presence of two witnesses.

ALBERT H. BUCKELEW.
